United States Patent

Des. 235,691
Patented July 1, 1975

235,691

HANDBAG

Valeria Barad, Gardena, Calif., assignor to Theodor
Manufacturing Corp., Gardena, Calif.

Filed May 29, 1973, Ser. No. 364,900

Term of patent 14 years

Int. Cl. D3—01

U.S. CL. D87—3 F

FIG. 1 is a side perspective view of a handbag showing my new design;

FIG. 2 is an end elevational view thereof;

FIG. 3 is a top plan view;

FIG. 4 is a side elevational view of the side opposite that shown in FIG. 1;

FIG. 5 is a bottom plan view; and

FIG. 6 is an elevational view of the side shown in FIG. 1 with the outside section shown in an open position.

I claim:

The ornamental design for a handbag, substantially as shown and described.
